CLAIM

The ornamental design for a cylindrical light fixture with fins, as shown and described.

DESCRIPTION

FIG. 1 is a top perspective view of a first embodiment of the new design;

FIG. 2 is a bottom perspective view of the first embodiment of the new design;

FIG. 3 is a front view of the first embodiment of the new design;

FIG. 4 is a rear view of the first embodiment of the new design;

FIG. 5 is a top view of the first embodiment of the new design;

FIG. 6 is a bottom view of the first embodiment of the new design;

FIG. 7 is a right side view of the first embodiment of the new design;

FIG. 8 is a left side view of the first embodiment of the new design;

FIG. 9 is a top perspective view of a second embodiment of the new design;

FIG. 10 is a bottom perspective view of the second embodiment of the new design;

FIG. 11 is a front view of the second embodiment of the new design;

FIG. 12 is a rear view of the second embodiment of the new design;

FIG. 13 is a top view of the second embodiment of the new design;

FIG. 14 is a bottom view of the second embodiment of the new design;

FIG. 15 is a right side view of the second embodiment of the new design;

FIG. 16 is a left side view of the second embodiment of the new design;

FIG. 17 is a front view of a third embodiment of the new design; and,

FIG. 18 is a front view of a fourth embodiment of the new design.

The broken lines in the drawings are provided to show environmental structure or boundaries that form no part of
